UNITED STATES PATENT OFFICE.

ROBERT W. HOWELL, OF KIRKWOOD, MISSOURI.

STOVE.

1,128,605.

Specification of Letters Patent. Patented Feb. 16, 1915.

Application filed April 5, 1912. Serial No. 688,785.

To all whom it may concern:

Be it known that I, ROBERT W. HOWELL, citizen of the United States of America, and resident of Kirkwood, St. Louis county, 5 Missouri, have invented a new and useful Stove, of which the following is a specification.

My invention appertains to heating stoves, and one object of the same resides in producing a stove of the character specified having means for reducing the fuel consumption.

A further object resides in providing a novel means for applying a down draft or 15 hot blast to the fire pot.

A still further object resides in providing a fire pot having a series of openings therethrough contiguous to its lower end and adapted to coöperate with other openings 20 formed in a vertically extending flue situated within the fire pot opposite the openings therein so that a hot blast may pass through the flame and out of said fire pot.

My invention consists in the construction, 25 arrangement and combination of elements hereinafter set forth, pointed out in my claims and illustrated by the accompanying drawing, in which—

Figure 1 is a longitudinal vertical section 30 of a stove embodying my improvements. Fig. 2 is a vertical section at right angles to Fig. 1 on the indicated line 2—3 of Fig. 1. Fig. 3 is a cross-section on the indicated line 2—3 of Fig. 1, in a direction opposite 35 to Fig. 2. Fig. 4 is a horizontal section on the indicated line 4—4 of Fig. 1. Fig. 5 is a horizontal section on the indicated line 5—5 of Fig. 1, the magazine being wholly removed.

40 In the construction of the stove as shown the numeral 10 designates a base adapted to be supported by legs 11 in a common manner. The base 10 preferably is constructed of sheet metal and a sheet metal shell 12 is 45 fixed to and rises from said base. A cast metal cover 13 is fixed to the upper margin of the shell 12 in a plane approximately parallel with and spaced from the base 10. The base, shell and cover may be of any desired 50 shape but I prefer the elliptical form as illustrated in Figs. 4 and 5. These parts may be connected in any desired manner. The cover 13 is provided with a smoke aperture and stove-pipe ring or ferrule 14 55 rounding the same, which aperture and ring preferably are located in the rear end por-

tion of said cover. The cover 13 also is formed with an aperture, preferably circular, in its front end portion and a fire-pot 15, preferably formed of molded metal, is 60 mounted in said aperture and extends within the front portion of the space inclosed by the shell. The fire-pot 15 preferably is suspended in a suitable manner from the cover 13. An ash chamber is formed by a 65 sheet metal ring 16 located in the forward portion of the shell beneath and of larger diameter than the fire-pot 15 and a grate frame 17 is supported on and fitted to the top of said ring and extends beneath the 70 lower end portion of said fire-pot. The grate frame 17 preferably is formed with lugs 18 and a grate 19 of suitable construction is mounted on said lugs over the ash chamber. The grate 19 may be provided 75 with a slidable portion or valve 20 of common construction adapted to be moved relative to the remainder of the grate and also adapted to be employed in connection with a removable tool (not shown) to shake the 80 grate and precipitate all or any portion of the contents thereof into the ash chamber. An extension or neck 21 projects through an aperture in the lower portion of the forward end of the shell 12 and a door 22 is hinged at 85 one end to said extension or neck and is connected at its opposite end by a latch 23 to the neck. The slidable portion 20 may be moved transversely of the grate 19 through the neck 21 so as to open a passage through the 90 center of said grate to the ash chamber. The central portion of the door 22 is apertured to form draft ports and a valve 24 overlies said ports and is carried by a hand screw 25 threaded in the center of the door. 95 The valve 24 may be closed against the outer face of the door 22 or be spaced therefrom by manipulation of the screw 25. A down draft or hot blast passage 26 is formed by mounting a plate 27 (which is U-shaped in 100 cross-section) on the inner front surface of the fire-pot 15. Both end portions of the plate 27 extend into contact with the fire-pot 15. Draft ports 28, of any desired number, are formed in the plate 27 and all of 105 said draft ports preferably are located near to and below the center of said plate.

A neck or collar 29 is mounted in the front of the shell 12 and communicates laterally with the upper end portion of the 110 fire-pot within the space inclosed by the plate 27, and a valve or damper 30 is mount-

ed on the outer end of said neck or collar and is adapted to be moved rotatively to close the same. A cover 31 is removably and replaceably mounted on and fitted over 5 the top of the magazine 36. A clean-out opening 32 is formed in the lower portion of the rear end of the shell 12 and normally is closed by a valve door 33. The fire-pot 15 is formed with smoke ports or vertical 10 slots 34 in the rear of its lower portion and the ring 16 is imperforate except for the aperture receiving the inner end of the neck 21. The cover 13 is formed with an annular bead 35 surrounding the hole provided for 15 insertion and removal of the fire-pot. The magazine is formed of an open ended cylinder 36 of sheet metal, fitting at its lower end within the upper end of the fire-pot 15 and extending upward therefrom. A drum 37, 20 of sheet metal and of the form of an inverted truncated cone, is arranged concentric with the cylinder 36, the lower (smaller) end of said drum surrounding and loosely engaging the bead 35 and resting on the 25 cover 13. The upper ends of the cylinder and drum are connected by a top ring 38 which projects circumferentially of the drum. The top ring 38 is formed with a hole to receive and pivot a lug 39 on 30 the cover 31 and also is formed with a series of spaced ports 40 affording communication between the interior of the drum and the exterior atmosphere. The drum 37 is designed to increase the radiating 35 surface of the stove and the hot air collected in the space between the magazine 36 and the drum is discharged to the surrounding atmosphere through the ports 40.

In the use of the stove as above described 40 a fire is laid on the grate 19 and valve 20, the fire-pot 15 is supplied with fuel, the cover 31 is placed over the magazine 36, the valve 30 is closed to the neck 29, and the valve 24 is opened by spacing apart from 45 the door 22. The parts being in such positions, direct draft is applied to the fire through the door 22 and grate 19 and flame, smoke and gases are discharged through the slots 34 into the combustion 50 chamber at the rear of the fire-pot and thence the smoke and unburned gases are carried away through the ferrule 14 and flue. When the fire is well started by the means described the valve 24 may be closed 55 to shut off the supply of atmosphere to the fire, and thereafter, as an increase of heat is desired, the valve 30 is opened to admit atmospheric air through the down draft passage 26 and ports 28 to the center and 60 lower portion of the fire-pot 15. The air entering through the passage 26 is heated to a considerable extent before it is applied to the fuel on the grate. The fuel settles by gravity from the magazine onto the grate 65 and supplies material for combustion there-

on. Experiment has demonstrated that coke, wood or coal of any of the kinds usually employed for fuel, various kinds of artificial fuel and the combinations of various fuels such as wood and coal, may be 70 supplied to the magazine and fed automatically to the grate and be wholly consumed thereon by down draft through the passage 26. The provision for shutting off the supply of atmospheric air through either of the 75 draft valves is of great importance in checking the combustion of fuel.

The magazine 36 is removable and may be removed when desired and when employed it as well as the fire pot, may be filled 80 with fuel, or any desired lesser amount of fuel may be used. The use and operation of the stove is the same, with or without the magazine, the latter having great efficiency 85 in that it increases the fuel capacity and surface for radiation.

The products of combustion such as smoke, soot and gas are carried rearwardly through the slots 34 into, and are consumed to the maximum degree within, the combustion chamber at the rear of the grate and fire-pot.

A valve 41 of common form may be provided in the cover 31 to supply air to the 95 top of the fuel.

I claim as my invention—

1. In a stove of the character described, the combination with a main casing, a supplemental casing disposed in the bottom thereof and forming an ash pit, means for placing said ash pit in communication with the exterior of the stove, a fire pot vertically disposed above said supplemental casing and having its lower end communicating therewith, a grate at the lower end of said fire pot, the latter having formed therein, contiguous to its lower end a plurality of laterally spaced longitudinally extending slots for establishing communication between the interiors of said fire pot and casing, a vertically extending flue formed on the inner surface of said fire pot opposite the slots therein, said flue being formed with a plurality of openings for cooperation with said slots and having its lower end closed and its upper end communicating with an opening formed in said fire pot contiguous to the upper end thereof, and means for placing the upper portion of said flue in communication with the exterior of the 100 stove substantially as and for the purpose set forth.

2. In a stove of the character described, the combination with a main casing, a supplemental casing disposed in the bottom thereof and forming an ash pit, means for establishing communication between the ash pit and the exterior of the stove, a fire pot vertically disposed above said ash pit and having its lower end communicating with 105 110 115 120 125 130

the latter, a grate disposed at the lower end of said fire pot, said fire pot having formed therein contiguous to its lower end, a plurality of longitudinally extending laterally spaced slots for establishing communication between the interiors of said fire pot and casing, a U-shaped plate disposed on the inner surface of said fire pot and extending longitudinally of the latter, said U-shaped plate being formed with a plurality of openings coöperating with the slots in said fire pot and having its upper and lower ends closed, the upper end of said U-shaped plate terminating contiguous to the upper end of the fire pot and communicating with an opening formed in the latter, also contiguous to its upper end, a laterally extending flue having one end communicating with the last mentioned opening in said fire pot and the other end thereof communicating with an opening formed in said main casing and a damper secured to said main casing over the opening therein, substantially as and for the purpose set forth.
